Primary Examiner — Darcey E Gottschalk(74) *Attorney, Agent, or Firm* — Christopher & Weisberg,
P.A.(57) **CLAIM**

The ornamental design for a genetic test device test unit, as shown and described.

DESCRIPTION

1. Genetic test device test unit

FIG. 2.1 : Front

FIG. 2.2 : Back

FIG. 2.3 : Top

FIG. 2.4 : Bottom

FIG. 2.5 : Left

FIG. 2.6 : Right

FIG. 2.7 : Perspective

FIG. 2.8 : Perspective (open drawer)

The portion identified with the solid lines shown in FIGS. 2.1 to 2.8 is the design being applied for registration; the portion with the broken lines shown in FIGS. 2.1 to 2.8 show portions of a genetic test device test unit that form no part of the design being applied for registration.

1 Claim, 8 Drawing Sheets(56)
